[57] CLAIM

We claim the ornamental design for a peninsular worksurface, as shown and described.

DESCRIPTION

FIG. 1 is a perspective view of a peninsular worksurface, showing our new design;

FIG. 2 is a top plan view;

FIG. 3 is a front elevational view;

FIG. 4 is a right-hand side elevational view; and

FIG. 5 is a left-hand side elevational view.

FIG. 6 is a top plan view of a second embodiment of the peninsular worksurface shown in FIG. 1; and,

FIG. 7 is a top plan view of a third embodiment of the peninsular worksurface shown in FIG. 1.

The surfaces or portions of the article not shown in the drawing or described in the specification forms no part of the claimed design.
